UNITED STATES PATENT OFFICE.

FREDERICK ERNEST KUBE, OF CLINTON, IOWA.

TURBINE.

1,394,772.

Specification of Letters Patent. Patented Oct. 25, 1921.

Application filed June 28, 1920. Serial No. 392,157.

To all whom it may concern:

Be it known that I, FREDERICK E. KUBE, a citizen of the United States, and a resident of Clinton, in the county of Clinton and State of Iowa, have invented a new and Improved Turbine, of which the following is a full, clear, and exact description.

This invention relates to improvements in turbines, and more particularly to steam turbines, an object of the invention being to provide a turbine having an improved construction of rotor in which the steam is admitted axially, then directed radially, and then circumferentially in contact with blades or vanes in a circular series so as to utilize the full kinetic energy of the steam in its passage in order to impart motion to the rotor.

A further object is to provide an improved arrangement of governors and valves for automatically obstructing the passage of steam so as to offer the maximum of resistance to the passage of steam in starting the rotor and to reduce the resistance as the rotor increases in velocity.

With these and other objects in view the invention consists in certain novel features of construction, and combinations and arrangements of parts as will be more fully 30 hereinafter described and pointed out in the claims.

In the accompanying drawings—

Figure 1 is a view in longitudinal section through the axis of my improved turbine.

Fig. 2 is a view partly in elevation and mainly in section on the line 2—2 of Fig. 1.

Fig. 3 is a view in section on the line 3—3 of Fig. 1.

Fig. 4 is a fragmentary view in section on the line 4—4 of Fig. 2.

1 represents a supporting frame in which a circular casing or stator 2 is fixed and supported in vertical position. The frame 1 is 45 provided with bearings 3 in which the turbine shaft 4 has rotary mounting and this turbine shaft may be provided with a pulley 5 or other suitable means for taking power therefrom.

50 The shaft 4 is in reality a pair of trunnions, one of said trunnions fixed to or integral with the rotor 6 of the turbine and the other trunnion connected by a head 7 and a series of lugs or pins 8 with the other side

55 of the rotor, and this head 7 and the pins 8 are accommodated in a lateral extension 9

forming an inlet compartment 10 positioned axially relative to the rotor. A steam inlet pipe 11 communicates with this chamber 10 and an exhaust pipe 12 projects tangentially 60 from the casing or stator 2.

My invention resides primarily in the construction and arrangement of rotor 6, and this rotor is in the form of a disk having a central or axial inlet 13 communicating with 65 the inlet chamber 10 and provided with a radial passage 14 which directs the steam from the axial inlet 13 to a circumferential steam passage 15 in the rotor.

This passage 15 is shown of circular shape 70 in cross-section and provided with a series of truncated conical shaped blades or vanes 16 fixed in the passage and spaced any desired distance apart. The passage 15 has its entrance end in communication with the 75 radial passage 14 and extends substantially the entire circumference of the rotor and has its outlet 17 in communication with the interior of the stator so that the steam exhausting therefrom may find outlet through 80 the exhaust pipe 12.

In the passage 15 I provide any desired number of butterfly valves 18 operated by weighted governor arms 19 on the outside of the rotor and connected by coiled springs 85 20 with the rotor, the springs tending to maintain the valves in their closed position. It will be noted, however, that the valves do not entirely close the passage, but leave a sufficient space for the passage of steam, 90 so that while the maximum of resistance is offered to the passage of the steam in starting, as the speed of rotation increases the governor arms 19 swing outwardly and turn the butterfly valves so as to offer less resistance to the passage of steam, and hence 95 automatically control said passage.

A steam gage 21 may be provided on the stator to indicate the pressure of steam therein and I may utilize any approved form of 100 packing or stuffing boxes, such as shown at 22, to render the stator steamtight.

In operation, the steam entering the chamber 10 is directed into the axial inlet 13, thence through the radial passage 14 and 105 thence through the circumferential passage 15, and in its movement through the latter passage, it finds abutment against the blades or vanes 16 causing the rotor to revolve.

As above stated, these blades or vanes 16 110 are of truncated conical form, thus providing free passages through the apexes of

the conical blades and said blades are so positioned as to form annular abutments, so that the kinetic energy of the steam is utilized to the maximum degree and is compelled to travel throughout substantially the entire circumference of the rotor and thereby economically drive the same. To prevent the bearing of the rotor from becoming overheated it is provided with a vacuum space V.

10 Various slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A turbine, comprising a stator, a rotor 20 in the stator having a circumferential passage discharging into the stator and having an axial inlet passage and a radial passage

connecting the axial inlet with the inlet end of the circumferential passage, abutments in the circumferential passage, valves in the circumferential passage adapted when in closed position to but partially close the passage, and governor arms connected to said valves and operated by the rotary motion of the rotor.

2. A turbine, comprising a stator, a rotor in the stator having a circumferential passage discharging into the stator and having an axial inlet passage and a radial passage connecting the axial inlet with the inlet end 35 of the circumferential passage, abutments in the circumferential passage, said circumferential passage having valve controlled passages therein, butterfly valves in said last-mentioned passages of less diameter 40 than the diameter of the passages, and governor arms controlling said valves.

FREDERICK ERNEST KUBE.
